UNITED STATES PATENT OFFICE.

JAMES BLACK WARES, OF OMAHA, NEBRASKA

AUTOMATIC FLUSH.

1,380,086.

Specification of Letters Patent. Patented May 31, 1921.

Application filed May 13, 1919. Serial No. 296,768

To all whom it may concern:

Be it known that I, JAMES B. WARES, a citizen of the United States, residing at Omaha, in the county of Douglas and State 5 of Nebraska, have invented new and useful Improvements in Automatic Flushes, of which the following is a specification.

This invention relates to flushing devices, particularly to those adapted for use in connection with urinals or toilets of any kind, 10 and has for its object the provision of a flush which is so constructed that the reservoir tank will be emptied at predetermined intervals whereby the urinals or other toilets 15 may be kept in a thoroughly sanitary condition.

An important object is the provision of a device of this character which is constructed entirely of metal and which eliminates the 20 use of moving parts whereby there will be nothing to get out of order or to wear, the flushing action being accomplished purely by siphoning.

An additional object is the provision of a 25 device of this character which will be simple and inexpensive in manufacture, highly efficient in service, durable in use, and a general improvement in the art.

With the above and other objects and advantages in view, the invention consists in the details of construction to be hereinafter more fully described and claimed, and illustrated in the accompanying drawing, in which—

35 Figure 1 is a longitudinal sectional view illustrating my device in all its details, and Fig. 2 is a horizontal sectional view on the line 2—2 of Fig. 1.

Referring more particularly to the drawing, the numeral 10 designates a tank which 40 may be formed of wood, metal, or other suitable material, and which may be of any desired size or shape.

Disposed within and extending through the bottom of the tank 10, is an outlet pipe 11 which is externally threaded for engagement thereon of a suitable waste pipe and also for engagement thereon of a pack nut 12 bearing against the bottom of the tank 50 at its underside. Intermediate its ends, the pipe 11 has formed thereon a circumferential flange 13 bearing upon the top of the bottom of the tank. Secured upon the upper end of the pipe 11 is a cylindrical shell 14 which is open at its upper end. A cylindri-

cal member 15 is disposed within the shell 14 and extends to the top thereof and this member 15 is preferably of the same diameter and forms, in effect, a continuation of the pipe 11. The space between the shell 60 14 and member 15 constitutes an annular chamber 16.

Supported within the tank 10 in any suitable manner is an inverted cylindrical shell 17 which extends outwardly beyond the shell 14 and which has its bottom end open and terminating between the upper surface of the bottom of the tank and the bottom of the shell 14. This shell 17 forms with the shell 14, an annular chamber 18. Formed 70 or secured upon the closed upper end of the shell 17 is a depending cylindrical member 19 which is disposed between the cylindrical member 15 and shell 14 and which terminates in spaced relation to the bottom of the shell 14. This member 19 forms with the shell 14, an annular chamber 20 communicating with the annular chamber 16 and the cylindrical member 19 forms with the member 15 an annular chamber 21, also 80 communicating with the chamber 16 and with the space 22 above the member 15.

Formed upon one side of the shell 17 is a casing 23 which is preferably cylindrical and which is of relatively small diameter 85 compared with the diameters of the above described shells. At its upper end, the casing 23 communicates through an opening 24 with the space above the shell 14 and at its lower end is provided with a nipple 25 providing an entrance opening of very small diameter.

Immediately above the member 15 the shell 17 is provided with an opening closed by a plug 26 through which extends one end 95 of an inverted U-shaped vent pipe 27 which extends above the top of the tank 10 and which has its other end extending through a hole in the plug 28 closing the top of the casing 23. This end of the pipe 27 extends 100 downwardly into the casing 23 and terminates above the bottom thereof. A second inverted U-shaped pipe 29 has one end extending downwardly into the pipe 11 and extends through a second hole in the plug 105 26 and has its highest portion terminating below the maximum water level in the tank 10. The bore of this pipe must be larger than the opening in the nipple 25. This upper portion of the pipe 29 is coiled to pro- 110

vide a convolution 30 and the other end of this pipe extends through a second opening in the plug 28 and downwardly adjacent the bottom of the casing 23.

- 5 The operation of the device is as follows:—

Assuming that the tank 10 is empty, the water entering the tank through any suitable inlet pipe, not shown, will rise through the 10 nipple 25 into the casing 23, and will also rise into the annular chamber 18, which it will fill. When the chamber 18 becomes full the water will flow over the top of the shell 14 and through the chamber 20 into the 15 chamber 16, whence it will flow into and fill the chamber 21. This forms an air trap within the chamber and space 22 and the parts are so arranged that this air trap will prevent water from rising sufficiently far 20 within the chamber 21 to flow into the member 15 and eventually the pipe 11. As the water rises within the pipe 29, which is initially supplied with water, an air trap will be formed within the convolution 30 until 25 the water level within the tank 10 reaches its maximum height, whereupon the air trap in the convolution 30 will be broken and the water will pass through the pipe 29 and into the pipe 11, causing a siphoning action, 30 which will reduce the air pressure in the space 22 and start a siphoning action in the pipe 11 which will drain the tank. As soon as the tank is empty, the cycle of operations will be automatically repeated.

35 From the foregoing description and a study of the drawing, it will be apparent that I have thus provided a simple and inexpensive automatic flush for urinals, toilets, and the like, which involves the use of 40 no moving parts and which also eliminates the use of gaskets, valves, and the like, and

which will consequently be free from any derangement.

While I have shown and described the preferred embodiment of my invention, it is of course to be understood that I reserve the right to make such changes in the form, construction, and arrangement of parts as will not depart from the spirit of the invention or the scope of the subjoined claim. 50

Having thus described my invention, I claim:—

In combination with a tank, an outlet pipe extending through the bottom of the tank, a cylindrical shell surrounding and spaced from the upper end of said pipe, an inverted cylindrical shell having its closed end spaced above the top of said pipe and said first named shell and having its wall extending outwardly of and in spaced relation to the first named shell and terminating below the bottom thereof, a cylindrical member depending from the top of said second named shell and disposed between said pipe and said first named shell, a relatively small upright cylindrical casing at one side of said inverted shell and communicating with the interior thereof at its top, the lower end of said casing being provided with an opening, a vent pipe having one end disposed within said casing, extending above the top of the tank, and having its other end discharging into said second named shell above said pipe, and a siphon pipe having one end disposed within said casing, having its highest point below the maximum level of water within said tank and having its other end extending downwardly into said outlet pipe, and said siphon pipe being provided intermediate its ends at its highest point with a convolution adapted to form an air trap. 65 70 75 80 85

JAMES BLACK WARES.
